[57] **CLAIM**

The ornamental design for an electrostatic copying machine, as shown and described.

DESCRIPTION

FIG. 1 is a front elevational view of the electrostatic copying machine showing my new design;
FIG. 2 is a front elevational view thereof in the operating state;

FIG. 3 is a top plan view thereof;

FIG. 4 is a right side elevational view thereof;

FIG. 5 is a left side elevational view thereof;

FIG. 6 is a rear elevational view thereof; and

FIG. 7 is a bottom plan view thereof.

FIG_1

FIG_2

FIG_3

FIG_7

FIG_4

FIG_5

FIG_6
